(57) **CLAIM**

I claim the ornamental design for a multifunction soft tissue mobilization instrument, as shown and described.

DESCRIPTION

FIG. 1 is top front left perspective view of the multifunction soft tissue mobilization instrument.

FIG. 2 is a bottom rear right perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is rear elevation view thereof.
